UNITED STATES PATENT OFFICE

96,207

DESIGN FOR A LACE

Henry Stenson, Long Eaton, England, assignor to
Gehring, Selemen & Birnbaum, Inc., New York,
N. Y., a corporation of New York

Application April 16, 1935, Serial No. 56,419

Term of patent 3½ years

To all whom it may concern:

Be it known that I, Henry Stenson, a British subject, residing at Long Eaton, England, have invented a new, original, and ornamental Design for a Lace, of which the following is a specification, reference being had to the accompanying drawing, forming a part thereof.

The single figure in the drawing is a plan view of a lace, showing between the dot and dash

lines, one repeat of the design which is repeated at regular intervals, the beginning and ending of similar repeats being shown lightly outside the dot and dash lines.

I claim:

The ornamental design for a lace as shown and described.

HENRY STENSON.
